UNITED STATES PATENT OFFICE.

JOHN B. WARING, OF NEW YORK, N. Y.

PULVERIZING-MACHINE.

SPECIFICATION forming part of Letters Patent No. 328,625, dated October 20, 1885.

Application filed July 24, 1884. Renewed June 15, 1885. Serial No. 168,799. (No model.)

To all whom it may concern:

Be it known that I, JOHN B. WARING, of New York, in the county and State of New York, have invented a certain new and useful Improvement in Pulverizing-Machines, of which the following is a specification.

I will describe a pulverizing-machine embodying my improvement, and then point out the various novel features in the claims.

10 In the accompanying drawings, Figure 1 is a central vertical section of a machine embodying my improvement, the section being taken transversely to the shaft; and Fig. 2 is a central vertical section of the machine taken 15 in the direction of the shaft.

Similar letters of reference designate corresponding parts in both figures.

A designates a chamber, consisting as here shown, of two rings, a and a' , intermatched so as 20 to form a tight joint, and two heads, a^2 and a^3 , fitted to the outer edges of the rings. Bolts a^4 , passing through the rings a and a' and through the edge portions of the heads a^2 and a^3 , secure the several parts together. At the center of the 25 interior surface of the rings a and a' is a circumferential recess, a^5 , into which is fitted a ring of steel, a^6 . The interior of this ring of steel is transversely concaved—or, in other words, is diametrically smaller at the side edges than 30 at the center. Externally it tapers transversely from the center to the edges. The bottom of the recess a^5 is tapered from the center to the edges to correspond with the exterior of the ring a^6 . Between the bottom of 35 the recess a^5 and the ring a^6 is preferably interposed a packing of india-rubber or analogous material, a^7 . The ring a^6 is clamped tightly between the rings a and a' . It can be removed and a new one substituted for it at pleasure. The packing a^7 enables the ring a^6 to be 40 clamped tightly, and yet allows for differential expansion and contraction between the parts.

The head a^2 is shown as quite flat, except at 45 the outer edge, where it is rounded inward, so that its interior surface is approximately coincident with the interior of the ring a . At the center of this head is an outwardly-tapering tubular portion, a^8 , through which the material to be pulverized enters the chamber. From the tapering portion a^8 a tube, a^9 , ex-

tends upward to a hopper, whence the material to be pulverized is fed to the chamber.

The head a^3 is of cone shape or tapering form from the ring a' to a central tubular portion, a^{10} , which extends outward and communicates with a tube, a^{11} . This tube a^{11} is shown as extending upwardly, and it is to be connected to a suction-blower, whereby a current of air is caused to flow through the machine. 55

The chamber A may be stationary, but preferably it will be capable of rotating. In the present example of my improvement the chamber is adapted to rotate; hence the tubular portions a^8 and a^{10} of the heads a^2 and a^3 are made externally cylindrical to serve as trunnions, and are supported in bearings a^{12} , comprised in standards a^{13} . The standards a^{13} are erected on base-pieces a^{14} , and secured thereto by bolts. 65

The tubes a^9 and a^{11} do not rotate with the chamber. Around the tubes a^9 and a^{11} , at their junction with the tubular portions a^8 and a^{10} of the heads a^2 and a^3 , packings b are applied. They may consist of rope saturated with tallow or 75 analogous material.

All the parts of the chamber A and the appurtenances thereof which I have described, excepting only the ring a^6 and the bolts, may be made of cast-iron. 80

In the chamber A are pulverizing-rollers B, which travel in close proximity to the interior surface of the ring a^6 . These rollers B are propelled by rollers C. The rollers B and C are combined with a carrier, D, whereby they 85 are revolved. As they revolve within the chamber A they rotate on their axes. The carrier D is affixed to a shaft, E. The shaft E extends through the chamber A and tubes a^9 and a^{11} . Where it passes through the tubes a^9 and a^{11} , sleeves a^{15} extend inwardly from the tubes around it, and disks a^{16} surround it closely outside the tubes to prevent leakage. The shaft is supported in bearings e , comprised in standards e' erected on the base-pieces a^{14} . 90

The carrier D consists, essentially, of two plate-like portions, d , an intermediate hub-like portion, d' , and connecting portions d^2 . It may be made in one piece and of cast-iron. 95

The propelling-rollers C are arranged upon shafts c , supported on the carrier; but the pulverizing-rollers B have no shafts. 100

The portions d^2 of the carrier are arc-shaped, and they form guards, preventing the rollers B from dropping down when the motion of the carrier stops.

5 When the machine is in operation, the propelling-rollers C force the pulverizing-rollers B around the chamber A. As soon as the pulverizing-rollers B acquire sufficient centrifugal force, they fly out close to the interior 10 surface of the ring a^6 , and thereafter they travel around such ring.

The rollers B C may advantageously be made of steel.

The material to be disintegrated is reduced 15 mainly between the ring a^6 and the pulverizing-rollers B.

The pulverizing-rollers B are made convex across the periphery, so as to correspond with the interior surface of the ring a^6 . The propelling-rollers C have their peripheries concaved. By making the rollers B C, respectively, convex and concave, and by making 20 the ring a^6 of the chamber A concave, the rollers B are guided, and all the rollers are centered relatively to each other and prevented 25 from moving laterally.

The rotary motion which the rollers B impart to the rollers C tends to neutralize the centrifugal force generated in the rollers C, for 30 the force with which the rollers B act upon the rollers C is exerted at such point as to tend to force the rollers C inward, or, in other words, toward the center of the chamber A.

35 Any material which may, by adherence to the pulverizing-rollers B, be carried around with the said pulverizing-rollers, will be further pulverized between these rollers and the propelling-rollers C.

40 To the carrier D is secured, by means of screws or otherwise, a plate or disk, F, which may be made of steel or iron. This plate or disk is considerably smaller diametrically than the interior surface of the ring a^6 . The suction-blower that is connected with the tube a^{11} induces a current of air through the machine. This current of air enters the tube a^9 , passes thence into the chamber A, passes around the 45 edges of the plate or disk F, and out of the tube a^{11} . The disk F serves to direct the air downwardly toward the lower portion of the chamber A. Were it not for said disk the air would be apt to pass directly through the chamber in an axial line.

50 If desirable, the current of air issuing from the chamber A, after passing to an apparatus wherein the great bulk of pulverized material is separated from it, may be returned by the blower to the chamber A, in order to be used over and over again, for the purpose of avoiding the waste of pulverized material which it may contain. When the current of air is thus returned, it will preferably re-enter through a branch, a^{11} , of the tube a^9 .

55 If desirable, the head a^2 may have a head like the head a^3 substituted for it, and then the material to be pulverized may be fed into each

head through a tube, a^{18} . (Shown in dotted outline in Fig. 1.) In such case the material to be pulverized may not only be fed into each 75 head of the chamber, but the pulverized material may be removed from each head.

The exterior of the rings a a' of the chamber A is adapted to receive a belt, G, which also passes around a pulley, H, on a rotary 75 shaft, H'. On the shaft H' is also affixed a pulley, H². A belt, I, passes around the pulley H², and also around a pulley, I', upon the shaft E. The shaft H' may be mounted in any suitable bearings and rotated by any desirable 80 motor. The belt I transmits motion from the shaft H' to the shaft E. The chamber A acquires a tendency to rotate in the direction in which the rollers B C revolve. The belt G, running on the pulley H, enables the driving- 85 shaft H' to resist this motion. To the extent to which the shaft H' resists the motion of the chamber A the chamber A aids in propelling the shaft H'.

By substituting for the pulley H pulleys of 90 different sizes the rate of speed at which the chamber will rotate will be varied.

The centrifugal force generated by the rotation of the chamber may of course be changed by varying the speed of the rotation of the 95 chamber. This can be done without altering the speed of the revolution of the rollers B C.

During the operation of the machine the material to be pulverized acquires a centrifugal force and flies out against the ring a^6 . The 100 pulverizing-rollers act on the material to be pulverized throughout the entire inner surface of the ring a^6 when the said material is distributed all around the ring a^6 ; hence the 105 wear of this ring is much more uniform than it otherwise would be. This also results in obviating the shocks which occur when pulverizing is done only at one part of the chamber of a pulverizer.

The force of the current of air which passes 110 through the chamber A may be varied by using a larger or smaller plate or disk, F, so as to contract or enlarge the space between the edge of the disk and the adjacent part of the chamber A.

By changing the speed of the rotation of the 115 chamber A and the force of the air-current passing through the chamber, material reduced to varying degrees of fineness may be delivered.

What I claim as my invention, and desire 120 to secure by Letters Patent, is—

1. In a pulverizing-machine, the combination of a chamber into which the material to be pulverized is introduced, loose pulverizing-rollers, a carrier, and rollers journaled in the carrier and serving to propel the pulverizing-rollers, substantially as specified.

2. In a pulverizing-machine, the combination of a chamber into which the material to be pulverized is introduced, loose pulverizing-rollers, a carrier, rollers journaled in the carrier, and guards comprised in the carrier for preventing the loose rollers from dropping

from the top to the bottom, substantially as specified.

3. In a pulverizing-machine, the combination of a chamber having a concave interior 5 surface for receiving the material to be pulverized, loose pulverizing-rollers having convex peripheries corresponding to the concave interior surface of the chamber, a carrier, and rollers having a concave periphery corresponding to the convex surface of the pulverizing-rollers, substantially as specified.

4. In a pulverizing-machine, the combination of a chamber, into which the material to be pulverized is introduced, loose pulverizing-15 rollers, a carrier, rollers journaled in the carrier and guards, and a disk attached to the carrier, substantially as specified.

5. In a pulverizing-machine, the combination of a rotary chamber, into which the material to be pulverized is to be introduced, pulverizing-rollers arranged within the chamber, and a carrier for revolving the pulverizing-rollers in the same direction as that in which the chamber rotates.

25 6. In a pulverizing-machine, the combination of a rotary chamber, into which the material to be pulverized is introduced, pulverizing rollers arranged within the chamber, a

carrier, and rollers journaled to the carrier and serving to propel the loose rollers, all the 30 said rollers being adapted to revolve in the same direction in which the chamber rotates, substantially as specified.

7. In a pulverizing-machine, the combination of a rotary chamber, into which the material to be pulverized is introduced, pulverizing-rollers arranged within the chamber, a carrier for the pulverizing-rollers, a belt from the chamber to a pulley on a shaft, and a belt from another pulley on the said shaft to a shaft 35 40 on which the said carrier is mounted, substantially as specified.

8. In a pulverizing-machine, the combination, with a horizontally-rotating chamber having hollow trunnions upon which said chamber rotates, and through which material to be pulverized may be received and discharged, of pulverizing-rollers arranged within the chamber and a carrier for revolving the pulverizing-rollers in the same direction as that 45 50 in which the chamber rotates.
